Primary Examiner — Rosemary K Tarcza*Assistant Examiner* — Alison Ofstun(74) *Attorney, Agent, or Firm* — Ostrolenk Faber LLP(57) **CLAIM**

The ornamental design for a multi-device charging station with wireless charging pad, as shown and described.

DESCRIPTION

FIG. 1 is a top, front perspective view of a multi-device charging station with wireless charging pad showing my new design;

FIG. 2 is a front view thereof;

FIG. 3 is a rear view thereof;

FIG. 4 is a right side view thereof, the left side view thereof being a mirror image;

FIG. 5 is a top view thereof; and,

FIG. 6 is a bottom view thereof.

The broken lines in the drawings illustrate environmental material that forms no part of the claimed design.
